UNITED STATES PATENT OFFICE.

WILLIAM R. COWAN, OF NEWARK, NEW JERSEY.

DESIGN FOR A CUP OR SIMILAR ARTICLE.

48,435.

Specification for Design.

Patented Jan. 11, 1916.

Application filed November 5, 1915. Serial No. 59,879. Term of patent 3½ years.

To all whom it may concern:

Be it known that I, WILLIAM R. COWAN, a citizen of the United States, residing at Newark, in the county of Essex and State of New Jersey, have invented a new, original, and ornamental Design for a Cup or Similar Article, of which the following is a specification, reference being had to the accompanying drawing forming part thereof.

The figure is a front and rear view of a cup showing my design.

I claim:

The ornamental design for a cup or similar article as shown.

WILLIAM R. COWAN.

Witnesses:

PAUL S. MAILER,
FRANK F. GROFF.
